UNITED STATES PATENT OFFICE.

ROBERT P. SWEENEY, OF GREENVILLE, SOUTH CAROLINA.

PNEUMATIC CLEANING APPARATUS.

Application filed November 14, 1924. Serial No. 748,987.

This invention relates to that class of pneumatic cleaning apparatus shown in my application 568830 filed June 16, 1922, though obviously it could be used for other purposes.

5 The principal object of the present invention is to improve what I denominate the induction chamber of the device, whereby the fluid under pressure exerts a maximum effect in drawing in the air through the cleaning 10 nozzle.

Another feature of the invention is the improved means provided for adjusting the nozzle in the induction chamber to get the maximum benefit of the fluid under pressure 15 while the cleaning apparatus is in operation.

Another feature of the invention resides in the provision of means for a stream line motion in the fluid under pressure at the end of the nozzle of the cleaning pipe.

20 Other features of the invention relate to the ease of adjustment of the nozzle in the induction chamber and the centering of the same as it is moved in and out.

With these and other objects in view which 25 will be apparent as the description proceeds, I will now describe my invention in connection with the accompanying drawings in which:

Fig. 1 is a view showing the device as applied to a pneumatic cleaner, the device being in side elevation.

Fig. 2 is a vertical median section showing the construction of the device with the Venturi-tube closed.

35 Fig. 3 is a view similar to Fig. 2 with the Venturi-tube opened.

Fig. 4 is a side elevation of the sliding jet tube.

Fig. 5 is a section on the line 5—5 of 40 Fig. 2.

Fig. 6 is a section on the line 6—6 of Fig. 2.

Fig. 7 is a section showing the construction of the suction nozzle with its reverse curves.

45 The apparatus comprises a tube 1 which may be connected to a suction nozzle as, for instance, the one shown in the aforementioned application. This tube 1 terminates just outside of my induction chamber and 50 there is attached to it in any convenient manner at 2, a nozzle 3. This nozzle is preferably of a uniform exterior diameter through most of its length and cone-shaped at its end as shown in Figs. 2 and 3.

55 My induction chamber comprises an outer shell 4 with an inlet 5 thereto on the end of

which may be attached a pipe connected with the pump or compressed air supply such as is also illustrated in my aforementioned application.

60 The interior of the shell 4, I preferably provide with ribs 6, so shaped that as the air passes through the compressed air pipe 5, keep the currents of compressed air from running together at the top and causing eddies, the 65 ribs 6 being shaped on stream lines as shown best in Figure 5 and directs the compressed fluid to flow through the right-hand side of the shell, Figs. 3 and 4, at all points around the end of nozzle 3, in an unbroken stream 70 thereby eliminating eddy currents and greatly increasing the efficiency of the apparatus. These ribs also serve the function of centering the nozzle 3 and guiding it in and out of the shell as shown in Fig. 5. On one 75 side of the shell 4 there is preferably formed a flange 7 and a packing chamber 8 to hold a packing to prevent leakage between the nozzle 3 and the shell or chamber 4.

Attached to the flange 7 as by screws 9 is a 80 screw-threaded sleeve 10 which may be extended into the packing box 8 to preserve the right pressure on the packing therein.

Embracing the threaded portion of the sleeve 10 is a second sleeve 12 screw-threaded 85 to co-act with the sleeve 10 at one end and at the other end provided with an encircling flanged ring 14. The nozzle 3 may conveniently be provided with a flange 15 having notches therein, not shown, through which 90 projections on the inner periphery of ring 14 may pass as in an ordinary bayonet joint construction, in assembling the ring 14 back of the flange 15 fitting between the ring 14 and a flange 16 on the sleeve 12. Holes 18 95 may be conveniently drilled through the embracing portions of the sleeves 12 and 14 which serve as sockets for the insertion of a pin to screw up or unscrew the sleeve 12 on the sleeve 10.

100 It will be apparent that as the sleeve 12 and ring 14 move in or out it will carry with it the nozzle 3 to coat near its end with a bushing 19 shown in detail in Fig. 7 and the relative positions of the end of nozzle 3 and 105 the interior of the bushing 19 are shown in Figs. 2 and 3. The interior surface of this bushing 19 it will be seen is on reversed curved lines at its end adjacent the end of the nozzle 3 which guides the inrushing fluid on stream 110 lines up to the nozzle 3 and due to its shape, it admits a large quantity of the fluid under

pressure up to this point to get the maximum benefit in drawing fluid through the nozzle 3.

By reversing the motion of the sleeve 12 and ring 14, the nozzle 3 can be moved to the position shown in Fig. 3 and it is apparent that the nozzle 3 may be adjusted at just that position where it co-acts with the interior surface of the bushing 19 to get the best effect from the compressed air rushing through the induction chamber. The ribs 6 also act to deliver the inrushing air in the proper direction to get the maximum effect with the power employed.

On the opposite side of the induction chamber from the sleeves 10 and 12, I may attach a flaring nozzle 21 similar to the nozzle shown in my aforementioned application which may lead the dust-laden fluid to the dust chamber 22 similar to the one shown in said aforementioned application.

It is apparent that various modifications of my invention may be made without departing from the spirit thereof and I do not wish to be limited to the exact construction shown except as herein indicated in the following claims.

What I claim is:

1. An induction chamber comprising a curved shell, a nozzle adjustable to and fro in the chamber, said chamber having a compressed air inlet and an outlet surrounding the one end of the nozzle, the portion of the chamber surrounding the end of the nozzle having reverse curves which coact with the curved shell to direct the air in stream lines forward of the nozzle into the outlet end, and means for adjusting the nozzle towards and away from said reverse curved portion.

2. An induction chamber comprising a shell having an air inlet and outlet, a nozzle therein, terminating within the outlet there being a space bounded by reversed curved surfaces between the nozzle and outlet, ribs on the interior of the shell for conducting the inrushing air on stream lines in front of the ends of the nozzle.

3. An induction chamber comprising a shell having an air inlet and outlet, a nozzle therein, terminating within the outlet there being a space bounded by reversed curved surfaces between the nozzle and outlet, ribs on the interior of the shell for conducting the inrushing air on stream lines in front of the ends of the nozzle, and means for adjusting the nozzle to and fro between the ribs in the shell.

4. An induction chamber comprising a shell having an air inlet and outlet, a nozzle therein, terminating within the outlet there being a space bounded by reversed curved surfaces between the nozzle and outlet, ribs on the interior of the shell for supporting and

centering the nozzle and conducting the inrushing air on stream lines in front of the ends of the nozzle, and means for adjusting the nozzle to and fro in the shell.

5. An induction chamber comprising a shell having an inlet and outlet, a nozzle in the shell, ribs on the interior of the shell adapted to guide the nozzle in its movements in or out of the shell and additionally to direct the inrushing air through the shell in stream lines forward of the nozzle, said shell having a portion near the end of the nozzle with reverse curves therein for cooperation with the ribs in directing the inrushing air on proper lines forward of the nozzle end.

6. An induction chamber comprising a shell, a nozzle therein, and means for moving the nozzle inwardly and outwardly in the shell, said means comprising a screw-threaded sleeve on the nozzle, a second screw threaded sleeve, and means on the nozzle cooperating with the second sleeve whereby when the second sleeve is rotated the nozzle will be moved inwardly or outwardly of the shell.

7. An induction chamber comprising a shell, a nozzle adjustable therein, a packing gland between the shell and nozzle, an externally screw-threaded sleeve adjustable towards and from the packing gland, and means cooperative with said screw threaded sleeve for moving the nozzle to and fro in the shell.

8. An induction chamber comprising a shell, a nozzle adjustable in the shell, a sleeve attached to the shell and externally screw-threaded, an internally screw-threaded sleeve cooperating with the external screw-threaded sleeve, a ring embracing and extending down over the end of the internally screw-threaded sleeve and having holes therethrough to act as sockets for facilitating the turning of the internally threaded sleeve to adjust it backwardly and forwardly relative to the shell, and means on the nozzle cooperative with the internally threaded sleeve and ring whereby when they are adjusted backwardly and forwardly relative to the shell, the nozzle will be adjusted backward and forward in the shell.

9. An induction chamber comprising a curved shell having an inlet and outlet, a nozzle normally passing through the curved shell, the inner surface of the chamber surrounding the end of the nozzle having reverse curves which coact with the outer surface of the nozzle to direct the incoming and outgoing fluids in stream lines forward of the nozzle end.

In testimony whereof I hereunto affix my signature.

ROBERT P. SWEENEY.
